UNITED STATES PATENT OFFICE

WILLIAM H. SHUFFLEBARGER, OF INDIANAPOLIS, INDIANA

SOLE-CEMENTING MACHINE

Application filed April 17, 1929. Serial No. 355,770.

This invention relates to shoe sole applying machines and has especial relation to machines for securing soles to shoes by the use of cement.

5 An object of the present invention is the provision of a machine of the above character whereby the upper and the sole are pressed together in a manner to force air outward from the center beyond the edges of the sole, and 10 thus avoid air pockets, and consequently more securely attach the sole in position.

Another object of the invention is the provision of novel means for providing a pneumatic support for the shoe during the sole attaching operation, and for holding said support in place so as to resist outward spreading movement, whereby the sole will be held in close contact with the upper throughout its entire area, and the formation of air 20 pockets between the sole and upper will thus be prevented.

Another object of the invention is the provision of a machine of the above character which is simple in construction, efficient in use, 25 and by means of which a sole may be attached to a shoe in a relatively short time and with a minimum amount of labor.

With the above and other objects in view, the invention further includes the following 30 novel features and details of construction, to be hereinafter more fully described, illustrated in the accompanying drawings and pointed out in the appended claims.

In the drawings:—

35 Figure 1 is a top plan view of a sole applying machine constructed in accordance with the invention.

Figure 2 is a side elevation of the same.

Figure 3 is an end view.

40 Figure 4 is a section on the line 4—4 of Figure 2.

Figure 5 is a detail perspective view of one of the removable end plates.

45 Figure 6 is a like view of the pneumatic supporting element or bag.

Figure 7 is a sectional view of the bag on the line 7—7 of Figure 6.

50 Figure 8 is a fragmentary rear view showing the bag holder with the rear plate removed.

Figure 9 is an enlarged fragmentary sectional view taken substantially on the line 9—9 of Figure 8.

Referring to the drawings in detail where-in like characters of reference denote corresponding parts, the reference character 10 indicates the base of the machine which may be of suitable size and shape and from which rise spaced standards 11. These standards support a bar 12 at their upper ends so that 55 this bar is spaced above and parallel with the base.

Mounted upon the base 10 are holders 13 which are designed to receive a pneumatic supporting element or bag 14, the latter being 60 designed to support the shoe while the sole is being applied.

Any number of these holders 13 and bags 14 may be provided, two being shown, so that soles may be simultaneously applied to a pair 70 of shoes indicated at 15. The bags 14 are removably positioned within the holders and for this purpose, one end wall 16 of each of the holders is removable. Headed studs 17 extend from the ends of the holders and the 75 removable ends 16 are provided with spaced slots 18 which receive these headed studs.

The bags 14 are preferably made of leather and are shaped to conform substantially to the shape of the holders. Inner rubber bags 80 or bladders 19 are positioned within the leather bags 14 and are adapted to be inflated through valves 20. The bags 14 may be formed as shown in Figure 6 and laced as indicated at 21, so that they may be readily 85 opened and closed and the bladders renewed when desired.

By reference to Figure 4 of the drawings it will be seen that the corners or edges of the bag are rounded and that the inner walls 90 of the holder 13 curve inwardly at their upper edges and prevent spreading of the bag when pressure is applied to its upper surface.

The reference character 22 indicates a pressure arm, one of which is provided for each bag holder. One end of this pressure arm carries a member 23 which is adapted to bear upon a last or tree 24 positioned within the shoe. Threadedly engaging the other 95 100

end of the pressure arm 22 is a rod 25 whose lower end carries a pressure foot 26 which is adapted to bear upon the upper of the shoe. The upper end of the rod 25 is provided with a squared extremity 27 to be engaged by a suitable handle or tool.

Threadedly engaging the bar 12 are threaded shafts 28. One of these shafts is provided for each bag holder and their lower 10 ends engage recesses or pockets 29 provided in the pressure arms 22. The upper ends of the shafts 28 are provided with squared portions 30 to be removably engaged by a hand wheel 31.

15 By operating the shafts 28, pressure may be applied to the shoe and as the latter is positioned upon the pneumatic supporting element or bag 14, pressure will be applied centrally of the shoe outward due to the fact 20 that the walls of the bag holder 13 confine the bag and resist its spreading movement. This action will cause air between the upper and sole to be forced outward and thus eliminate the formation of air pockets.

25 Also mounted upon the base 10 between the standards 11 is a sole board or shield 32, upon which the shoe sole may be placed while being roughened and prepared for cementing. A clamping screw 33 which is threadedly mounted in a bar 34 serves to clamp the shoe sole in place during this operation. The screw 33 is provided with a squared tool or wheel receiving portion 35, whereby the screw may be adjusted.

30 The invention is susceptible of various changes in its form, proportions and minor details of construction and the right is herein reserved to make such changes as properly fall within the scope of the appended claims.

40 Having described the invention what is claimed is:—

1. In a shoe sole applying machine, a base, a bag holder mounted upon the base and including side and end walls, one of said walls 45 being removable, a pneumatic bag removably located within the holder with the upper face of said bag exposed for engagement by the sole of a shoe, and means to apply downward pressure to the top of the shoe.

50 2. In a shoe sole applying machine, a base, a bag holder mounted upon the base and including side and end walls having their inner faces curved inwardly at their upper edges, one of said walls being removable, a pneumatic bag removably fitted within the holder and having its upper face exposed for engagement with the sole of a shoe, and means to apply downward pressure to the top of the shoe.

55 3. In a shoe sole applying machine, a base, a bag holder mounted upon the base and including side and end walls having their inner faces curved inwardly at their upper edges, one of said walls being removable, a pneumatic bag removably fitted within the holder

and having its upper face exposed for engagement with the sole of the shoe, and means including a shoe last engaging member to apply downward pressure to the shoe.

In testimony whereof I affix my signature. 70
WILLIAM H. SHUFFLEBARGER.
